UNITED STATES PATENT OFFICE.

BENJAMIN DAY CHAMBERLIN, OF CORNING, NEW YORK, ASSIGNOR TO EMPIRE
MACHINE COMPANY, OF PORTLAND, MAINE, A CORPORATION OF MAINE.

MECHANISM FOR GATHERING GLASS.

1,117,322.

Specification of Letters Patent.

Patented Nov. 17, 1914.

Application filed April 20, 1911, Serial No. 622,390. Renewed April 3, 1914. Serial No. 829,379.

To all whom it may concern:

Be it known that I, BENJAMIN D. CHAMBERLIN, a citizen of the United States of America, and a resident of Corning, New York, have invented certain new and useful Improvements in Mechanism for Gathering Glass, of which the following is a specification.

In the prior application filed by me on the 10 23rd day of March 1910, Serial No. 551,198, I have disclosed a machine in which an iron is presented to and inserted in a furnace mouth and then dipped into the glass from which a gather is to be made.

15 My present invention comprises means by which the extent to which the iron is dipped is controlled by the level of the glass itself so that as the level is lowered in using from it the iron successively follows it down in dipping. For this purpose I provide a dip regulator, which itself is controlled by the level of the glass and to which the gathering machine surrenders the control of the iron temporarily while the gather is being effected. 20 In this aspect my invention is capable of numerous embodiments, and it further consists in the construction, arrangement and combination of several parts which constitute the embodiment which is 25 herein shown as an example of my broad invention.

Referring to the accompanying drawings in which corresponding parts are designated by corresponding marks of reference. Figure 35 1 is a fragmental vertical section through the furnace and machine embodying my invention. Fig. 2 is a plan view thereof partly in section. Fig. 3 is a fragmental front elevation of mechanism attached to the furnace. Fig. 4 is a fragmental plan view of the gather iron and its controlling arm.

The gathering machine shown in the accompanying drawings is of the general type disclosed in my prior application #551,198 hereinbefore referred to and comprises a frame rotating in the direction of the arrow (Fig. 2) around a vertical axis and having a series of radially disposed arms 2 projecting from the periphery thereof, in each of 45 which arms is pivoted by a vertical axis a frame 3 carrying in its outer end the horizontal trunnion 3^a of the support 3^b of the gather iron 3^c. The rotation of the frame and the movement of the pivoted arms thereon will bring the several irons carried there-

by successively past the mouth of the furnace 4, and will insert and withdraw the pipes in and from the furnace mouth and also maintain them there for a time sufficient to permit the gather to be effected. Inasmuch as the mechanism for accomplishing these movements of gather iron forms no part of this invention it need not be described herein.

The movement of the gather iron support 65 allowed by its horizontal trunnion, when the end of the blow-pipe is inserted in the furnace, provides for the dipping of the iron into the glass from which the gather is to be made. In my said prior application 70 this movement of the gather iron on its horizontal axis for this purpose and for other purposes is effected by appropriate gearing controlled by a fixed cam disk and is always due to the shape of the cam run 75 therein. In my present invention I still retain the cam run for accomplishing the vertical motion of the iron other than that actually gathering, but for this latter purpose, I cut away a portion of the cam run so that 80 the iron at the gathering time is no longer under the control thereof. As shown in the drawings in my prior application the general vertical control of the iron is effected by a fixed cam disk 5 which by its cam run 85 5^a controls the movement of the radial slide bars 6 and through the gear wheels 6^a, 6^b and 6^c and beveled gears 6^d, 6^e, 6^f and 6^g the latter of which is fixed upon the rear end of the trunnion 3^a of the blow-pipe. I however for the purposes of this invention cut away a portion 5^b of the cam run 5^a at that wall thereof which arrests or controls the lowering of the blow-pipe, at the point which should control the radial movement 90 of each slide bar during the time the gather iron of that unit is inserted in the furnace. Thus during the gathering the gathering machine has no function other than to form a pivot upon which the gather iron is moved 95 to effect the gather and to provide for the rotation of the iron around its longitudinal axis. This latter is accomplished by mechanism similar to that of my prior application.

The furnace 4 is adapted to coöperate 105 with the mechanism before described and has therein the usual pot 4^a containing molten glass and located opposite the mouth 4^b of the furnace. A float 7 of some refractory material is contained within the pot 110

2

and rests upon the surface of the molten glass therein and has a standard or projection 7^a upon its upper surface, upon which rests the inner end of an arm 8, which projects outwardly through the upper part of the mouth of the furnace and is pivoted intermediate of its length at 8^a in the upper part of such opening to a bracket casting 9 fastened to the outside wall of the furnace.

5 The opposite end of this lever extends upwardly and is connected by the outwardly extending adjustable slotted link 10 to the medial portion of the lever 11, the upper end of which is pivoted at 11^a to the bracket casting. The lower end of the lever carries a cross bar or track 12 upon its forward face, the ends of which are beveled as at 12^a and which is properly shaped to maintain a proper dipping of the iron in the molten glass during the period necessary to effect the gather. This control by the bar of the iron is provided for by securing to the iron support 3^b a rearwardly extending arm 13 carrying a roller 13^a in its end, which roller, 10 when the gather end of the iron is in the furnace, will lie under the track 12, the gather end of the iron at such time being above an opening 7^b formed in the float 7. As thus constructed, when an iron carried 15 by the main frame is projected into the furnace mouth by the movement of the former and of the arm 2 in relation thereto, the radial slide bar 6 corresponding to such arm will be opposite the cut away portion 20 of the cam run 5^a and the machine will thus lose control of the iron in so far as relates to the elevation of the gathering end thereof. Such end of the iron will thus drop until arrested by contact between the 25 roller 13^a carried on its support and the track formed by the bar 12 attached to the furnace. The elevation of the gather end of the iron is now controlled by the bar and will depend upon the contour given the 30 same and to its angular position around its pivotal point 11^a. The latter of these is automatically regulated by the level of the glass in the pot by the mechanism which has been described, the lowering of the level 35 causing the descent of the float and the corresponding inward movement of the bar 12. The leverages between the float and the bar and between the end of the gathering iron and the roller 13^a on the arm 13 thereof are 40 such that the elevation of the gathering end of the iron will be varied in successive gathers precisely in the same rate that the level of the glass varies and thus a uniform immersion of the iron in successive gathers 45 will be maintained. The continued motion of the main frame will, after elapse of a proper time to properly effect the gather bring the radial slide bar of the gathering iron into contact with the curve which terminates the cut away portion 5^b of the cam

run; and the machine again assumes control of the elevation of the iron, raising the end thereof to permit the withdrawal of the same from the furnace mouth.

Having thus described my invention what I claim and desire to secure by Letters Patent is:

1. The combination with means for inserting a gathering device into a furnace, of means for regulating the lowering of such device to effect the gather by variation of the level of glass in the furnace.

2. The combination with means for inserting a gathering device in a furnace, withdrawing it therefrom and for varying the elevation of the gathering end of the blowpipe when withdrawn, of means controlled by the elevation of glass in the furnace for regulating the dipping of the device when in the furnace.

3. The combination with a mechanism adapted to insert a gathering device into a furnace and to withdraw it therefrom and to afford a support for the device when in the furnace, of means controlled by the level of glass in the furnace from varying the inclination of the device upon its support.

4. The combination with a pivotal mounting for the gathering device, of a gathering device mounted thereon and projecting within the furnace, a float within the furnace and mechanism for shifting the gathering device upon its pivot by a variation of level of the float.

5. The combination with a glass furnace of a gathering device, a float contained within the furnace and means regulated by the elevation of the float to control the elevation of the end of the gathering device.

6. The combination with a furnace of a blowpipe support and means controlled by the glass level in the furnace for regulating the position of the device carried by the said support.

7. The combination with a glass furnace, of a traveling support for a gathering device, a gathering device carried in the said support, means controlled by the travel of the support for moving the same around a horizontal axis when the device is out of the furnace and means controlled by the level of the glass in the furnace for regulating the movement of the support around its horizontal axis when the device is in the furnace to effect the gather.

8. The combination of a glass furnace, of a traveling support for a gathering device, a gathering device carried in the said support, means controlled by the travel of the support for moving the same around a horizontal axis when the device is out of the furnace, a track supported adjacent to the furnace mouth and adapted to regulate the movement of the device support when the device is in the furnace and means con-

trolled by the level of the glass in the furnace for regulating the position of the said track.

9. The combination of a glass furnace, of a traveling support for a gathering device, a gathering device carried in the said support, means controlled by the travel of the support for moving the same around its horizontal axis when the device is out of the furnace, a track supported adjacent to the furnace mouth and adapted to regulate the movement of the device support when the

device is in the furnace, a float contained within the furnace and a connection between the float and track whereby the position of the track is controlled by the level of the glass in the furnace. 15

In testimony whereof I have set my hand in the presence of two witnesses.
